UNITED STATES PATENT OFFICE.

JAMES B. LADD, OF ARDMORE, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

CENTRIFUGAL METAL-PIPE MOLD.

Application filed July 12, 1922. Serial No. 574,489.

To all whom it may concern:

Be it known that I, JAMES B. LADD, a citizen of the United States of America, and resident of Ardmore, in the county of Montgomery, in the State of Pennsylvania, have invented a certain new and useful Improvement in Centrifugal Metal-Pipe Molds, of which the following is a true and exact description, reference being had to the accompanying drawings, which form a part thereof.

My invention relates to the construction of metal pipe molds used in the manufacture of centrifugally cast pipe and, in ordinary practice, cooled by water in contact with their outer surfaces. In the use of such molds, which are long and relatively narrow, they have been very generally enlarged at one end so as to provide for the formation of a bell end on the pipe. The exterior of the mold is maintained at a low temperature, generally somewhere below 200° F. While the interior of the mold, which is in contact with the melted metal poured into the mold to form the casting, is normally heated to a quite high temperature so that the interior portion of the mold tends to expand but is restrained by the cool exterior portion of the mold. Obviously, therefore, during the pouring of the metal, the interior of the mold will be compressed by this expansive action and this compression may well be beyond the elastic limit of the metal. Again, after the casting is made and after it is withdrawn from the mold, the interior portion of the mold, of course, is cooled and tends to contract, and this contraction is also resisted by the cool exterior of the metal mold. Obviously, the strains to which the metal is exposed, for the reasons above stated, operate both circumferentially and longitudinally and it has been found in practice that these strains have a tendency to destroy the smooth interior surface of the mold so that it becomes more or less rough and some times shows slight fissures, and this roughening of the interior surface of the mold is particularly apt to occur at or near the point where the cylindrical surface of the metal merges into the enlargement provided for the formation of the bell.

The object of my invention is to so construct the mold as to obviate, to a large extent, the tendency of the expansive and con-

tractive strains to roughen the inside of the mold and I accomplish this by cutting narrow slots or grooves in the inside of the mold so as to divide the inner surface of the mold into separate segments, in which segments the metal can expand and contract with approximate freedom and without exerting destructive strains on the mold surface. The slots must be so narrow that the melted metal poured into the mold will not penetrate into them even under the considerable pressure due to the rapid rotation of the centrifugal mold. At the same time the slots should be sufficiently broad, and should divide the inner surface of the mold into segments of such size, that these segments can expand and contract freely. The slots are of such dimensions that the chilling effect of the cooled metal on the mold will prevent the entry of the fused metal into the slots. The slots should be from one hundredth to two hundredths of an inch wide according to the temperature and nature of the fluid metal used.

Referring now to the drawings in which my invention is illustrated.

Figure 1 is a longitudinal section of a centrifugal pipe mold constructed in accordance with my invention.

Figure 2 is a cross section through such a mold shown on an enlarged scale.

Figure 3 is a view of a segment of the mold shown on a still larger scale.

Figure 4 is a face view of a segment of the inside of the mold shown on a scale similar to that of Fig. 3, and

Figure 5 is a view showing a modification in the way of forming the circumferential slots.

A indicates the mold. B the ring for forming the smaller end of the pipe casing. C the core for forming the bell end of the casing. D, D, etc. are longitudinally running narrow slots extending, as shown, through the length of the mold, and E, E, etc. are circumferential narrow slots intersecting the longitudinal slots, as best shown in Fig. 4. In Fig. 1, only one of the longitudinal slots is shown but it will be understood that such slots are evenly disposed around the circumference of the mold, as indicated in Figs. 2, 3 and 4. The value of the slots is particularly great at the point where the cylindrical portion of the mold

merges into the enlarged portion indicated at A' and ordinarily it will be sufficient to form a mold with only longitudinal slots, although circumferential slots are desirable but would add considerably to the cost of manufacture:

It will be obvious that in place of making the circumferential slots separate from and parallel to each other they can be made 10 of helical form, as indicated at E' in Fig. 5.

Having now described my invention, what I claim as new and desire to secure by Letters Patent, is:

1. A long and relatively narrow centrifugal metallic pipe mold having its inner surface divided into separated segments by narrow slots or grooves which are too narrow to permit the fluid metal for the pipe casting to enter under the condition of use 20 and which diminish the strains caused by the alternate heating and cooling of the inner portion of the mold.

2. A centrifugal pipe mold formed of a long and relatively narrow solid metal cylinder having its internal surface divided into separated segments by narrow slots or grooves which are too narrow to permit the

fluid metal for the pipe casting to enter under the conditions of use and which diminish the strains caused by the alternate heating 30 and cooling of the inner portions of the mold.

3. A long and relatively narrow centrifugal metallic pipe mold in the form of a cylinder with one end enlarged to form the bell end of a pipe having its inner surface adjacent to the point where the mold enlarges into the bell formed with narrow slots or grooves too narrow to permit the inflow of melted metal under conditions of use and whereby the strains caused by expansion and contraction of the inner portions of the mold are diminished.

4. A centrifugal long and relatively narrow metallic pipe mold having its inner surface divided into separated segments by narrow slots or grooves running both longitudinally and circumferentially which are too narrow to permit the fluid metal for the pipe casting to enter under the conditions of use and which diminish the strains caused by the alternate heating and cooling of the inner portion of the mold.

JAMES B. LADD.
